UNITED STATES PATENT OFFICE.

ALLAN EDWARD LARD, OF ST. JOSEPH, MISSOURI.

SINGLE-TRIGGER MECHANISM FOR FIREARMS.

SPECIFICATION forming part of Letters Patent No. 674,508, dated May 21, 1901.

Application filed June 21, 1899. Serial No. 721,281. (No model.)

To all whom it may concern:

Be it known that I, ALLAN EDWARD LARD, of St. Joseph, in the county of Buchanan and State of Missouri, have invented certain new and useful Improvements in Firearms; and I do hereby declare that the following is a full, clear, and exact description thereof, reference being had to the accompanying drawings, and to the letters of reference marked thereon, which form part of this specification.

This invention relates to the firing mechanism for firearms of that class set forth in my prior application, Serial No. 676,091, filed April 1, 1898.

The invention consists in the matters hereinafter fully set forth, and defined in the appended claims.

The invention is herein shown in connection with a shotgun provided with two shotgun barrels and locks or firing mechanisms embracing two hammers, together with means for actuating the same by successive pulls on the trigger. The invention, however, may be applied to firearms of other kinds and to those having more than two barrels.

In the drawings, Figure 1 is a view in side elevation of the breech mechanism of a double-barreled shotgun made in accordance with my invention. Fig. 2 is a section taken on line 2 2 of Fig. 1. Fig. 3 is a section taken on line 3 3 of Fig. 1. Figs. 4 and 5 are details of mechanism for reversing the order in which the barrels are discharged. Fig. 6 is a top plan view of movable firing-lugs constituting part of my invention. Fig. 7 is a section taken on line 7 7 of Fig. 1. Figs. 8 and 9 are side elevations, partly in section, of the firing mechanism, showing the positions the parts assume during the operation thereof.

As shown in the drawings, A indicates the body or wooden portion of the gun-stock; B, the frame; C, the barrels, which are pivoted to the forward extension of the frame.

E indicates a snap-lever by which the locking-detent holding the barrels in place is actuated.

G is a trigger-plate to which the trigger is pivoted and upon which, in the particular instance illustrated, the main parts of the firing mechanism are mounted. The locks are shown as being provided each with the

usual hammer or tumbler F, mainsprings F', sear F², and sear-spring F³. The frame is provided at its forward end with two cocking-levers F⁴, which extend into a recess d in the forward extension D and which are actuated in the depression of the forward end of the barrels at the time of loading, so as to cock or throw back the hammers in the usual manner.

Now referring to the firing mechanism by which the sears F² are actuated for releasing the hammers, the same in the particular embodiment of my invention herein shown is constructed as follows:

J indicates the trigger, which is pivotally mounted on a trigger-standard G', which is integral with the said trigger-plate and projects upwardly within the frame. The said trigger is provided with an upwardly and rearwardly extending trigger-blade J', made integral therewith and which takes the place of the firing-plate described in my previous application. The said trigger-blade is provided in its rear end with a horizontal rearwardly-opening slot j, in which is secured a movable firing-block (indicated as a whole by K) and which is provided on its opposite sides with laterally-projecting lugs K' K², which are offset from each other, or, in other words, one placed in advance of the other, so that when one of the said lugs is in position for contact with one sear the other of said lugs will necessarily be at the front or rear of the other sear. Preferably and as shown the said firing-block is provided on each side thereof with depressions k' k² below the surface of the lug proper. On one side the said depression is in front of the firing-lug and on the other side it is behind the lug, the parts being so arranged that the end of the sear in the undischarged side of the gun will rest in one of said depressions after the discharge of the first barrel. The lower margin of the slot at the rear end of the trigger-blade is, as shown, provided with a guide-rib j^a, Fig. 7, and the movable firing-block K is provided on its under surface with a longitudinal groove complementary to the said rib, so that when the said firing-block is inserted in the trigger-blade free longitudinal movement thereof is permitted, while lateral movement is made impossible by reason

of the aforementioned guide-rib engaging the said groove. A pin k^3 depends from the under side of the lug to a point near the trigger-plate G, and the lower end of the said pin is engaged with a transverse slot in the forward end of a shifting bar k^4 , which slides longitudinally upon the inner side of the trigger-plate. The forward end of the said shifting bar is provided with a lateral stud k^5 . A spring k^6 (herein shown as having the form of a leaf-spring) is secured at one end upon the said trigger-plate, and the free end thereof presses downwardly upon the said stud k^5 , so as to hold the shifting bar from accidental movement. Preferably the free end of the said leaf-spring will be provided with two bends or notches so disposed that when the shifting bar is slid rearwardly the notch near the extremity of the free end of the leaf-spring will engage the stud k^5 , and thereby hold the firing-block K in position to engage the right sear first, while if the shifting bar is slid forward the said block K will also be moved to its forward position and the stud k^5 will engage the forward notch in the spring, the parts then being in a position adapted to discharge the left barrel first. Convenient means for actuating the said shifting bar is afforded by providing a longitudinal slot in the trigger-plate adjacent to the trigger-guard and by securing to said shifting bar a thumb-piece or slide k^7 by means of a stud passing through said slot. The thumb-piece k^7 , which actuates the shifting bar k^4 , will preferably for actual use be located opposite the rear end of the trigger-guard. It is shown at the rear merely for clearness.

A spring J^2 is applied to the trigger-blade in such manner that it tends to lift the rear end of the same. In the particular details of construction illustrated the trigger-blade J' is provided upon its upper edge with a lug j^2 , and the trigger-standard G, on which the said trigger-blade is pivoted, is provided with an upward projection g , while the spring J^2 has the form of a coiled contractible spring secured to the lug j^2 and the projection g , so as to normally hold the trigger-blade elevated and in such position that one of the firing-lugs always presses against or is in contact with one of the sears. The sear-springs are so much stronger than the spring J^2 as to avoid possibility of either sear being moved or actuated by the pressure of said spring alone.

L indicates a detent which is movably supported upon the trigger-blade and is herein shown as having the form of a forwardly and upwardly projecting prong or spur on the lower end of a detent-lever N, which is pivoted to the trigger-blade, near the top of the same, by means of the pivot n and is adapted to engage a rearwardly and downwardly projecting holding or locking tooth m, formed on the top of the detent-post M. Said post M is pivotally attached to a lug G^2 , which is formed on the trigger-plate G at a point forward of the detent-lever N. The said detent-

lever N is actuated by a spring N', applied in such manner that it tends to throw the upper part of the lever forward. Conveniently said spring N' has the form of a coiled push-spring held in compression between a lug on the trigger-blade and the lower part of the lever N, at a point below the pivot thereof.

A holding-dog O, having the form of a bar or rod, is pivoted on the rear end of the trigger-blade, so as to swing in a plane parallel with the sides thereof, and the free end of said dog is adapted to swing forwardly into position to engage the lever N at a point below its pivot n , and thereby limit the rearward movement of the detent L. The said dog is provided on each side thereof with laterally-projecting studs o and o', which extend into a position to be engaged by either one of the sears. Inasmuch as the said dog swings on one side of the trigger-blade, a curved slot is provided in the same, through which one of the said studs projects to a point above the sear on that side of the said trigger-blade. Upon the lifting of either sear to discharge either barrel the end of the sear which is lifted engages one of the said studs, and thereby lifts the free end of the dog out of engagement with the lever N. The front edge of the detent-post M extends downwardly into position to engage the trigger-plate or a projection thereon, and thereby limits the forward movement of the top of said post. A spring M', preferably having the form of a push-spring, engages the lower end of said lever, on the front side thereof, and tends to hold the lower end of the same constantly in contact with the trigger-plate and the upper end of said post at the forward limit of its movement. A sliding weight I is provided at the rear of said levers N and M, the same consisting of a straight bar of metal provided on its upper side with an upwardly-projecting arm or stud I', which is adapted to engage a lateral stud n^3 in the lower end of the detent-lever N. The front end of the weight extends forwardly beyond the said arm sufficiently far to engage the bottom of the lever M at the same time that the arm I' engages the stud n^3 of the lever N. Said weight I slides in a groove in the inner side of the trigger-plate and is secured longitudinally therein by means of the lugs i i on each side of the said weight. A pin i' passes through the top of the said lugs to prevent the weight from being thrown out of the slot in the trigger-plate. A pulling-spring I² is secured by one of its ends to the rear end of the said weight, and the other end of the same is secured to a stud i^3 , secured upon the inner side of the trigger-plate. The normal action of the said spring is to hold the said weight retracted or in its rearmost position and out of contact with the lower end of the lever M and the said stud n^3 . The strength of the said spring I² is not sufficient, however, to prevent the said weight being thrown forward by the recoil of

prevented. When it is desired to use the arm, the safety-catch is moved forwardly, by pressure of the finger on the slide, out of engagement with the stud on the trigger-blade, 5 thereby leaving the same free to move upwardly, as previously described.

So far as the operation of the device for changing the order of firing is concerned, the operation of said devices will be the same whether the part herein called the "trigger-blade" be rigidly attached to the trigger or whether it have a limited movement with respect to the trigger, as is the case with the firing-plate shown in said prior application hereinbefore referred to. The same is true also of the safety-catch hereinbefore described, it being obvious that the same is applicable to the construction of the other parts shown in said prior application, as well as to 20 that hereinbefore illustrated.

I claim as my invention—

1. The combination with a plurality of locks and the sears thereof, of a firing mechanism comprising a single trigger provided with a rearwardly-extending rigidly-attached trigger-blade, a spring-actuated detent on the trigger-blade, a tooth on the frame adapted to be engaged by the detent on the trigger-blade, holding means acting on the said detent to retain the latter in position for engagement with said tooth and adapted for actuation by the sears to release said detent, and means operated in the act of loading the arm acting on the detent to place it in interlocking relation with the tooth preparatory to the firing of the first barrel.

2. The combination with a plurality of locks and the sears thereof, of a firing mechanism comprising a single trigger provided with a rearwardly-extending rigidly-attached trigger-blade, a spring-actuated detent-lever pivoted to the trigger-blade, a tooth on the frame adapted to be engaged by said detent-lever, a pivoted holding-dog on the trigger-blade adapted to engage the detent-lever and which is adapted for actuation by the sears and a rod which is moved in the act of loading the arm and which acts on said detent-lever to place same in interlocking relation with the tooth.

3. The combination with a plurality of locks and the sears thereof, of a single trigger provided with a rearwardly-extending rigidly-attached trigger-blade, a spring applied to lift the rear end of the trigger-blade, a spring-actuated detent-lever pivoted on the trigger-blade, a tooth on the frame adapted to be engaged by said detent-lever, a holding-dog on the trigger-blade adapted to engage the detent-lever and which is adapted for actuation by the sears, and a rod which is moved in the act of loading the arm and which acts on said detent-lever.

4. The combination with a plurality of locks and the sears thereof, of a single trigger provided with a rearwardly-extending rigidly-attached trigger-blade, a spring-actuated de-

tent-lever pivoted to said blade, a tooth on the frame adapted for engagement with said detent-lever, a pivoted holding-dog on the 70 blade adapted to engage the detent-lever and which is adapted for actuation by the sears, a rod which is moved in the act of loading the arm and which acts on said detent, and a movably-supported weight adapted to strike, and 75 arrest the rearward movement of, the detent-lever.

5. The combination with a plurality of locks and the sears thereof, of a single trigger provided with a rearwardly-extending, rigidly-attached trigger-blade, a spring-actuated detent-lever pivoted to the trigger-blade, a spring-actuated detent-post pivoted to the frame, a pivoted holding-dog on the trigger-blade adapted to engage the detent-lever and 80 which is adapted for actuation by the sears, a rod which is moved in the act of loading the arm and which acts on said detent-lever and a movably-supported weight which acts on 85 said detent-post to throw the same into position for engagement with the detent-lever.

6. The combination with a plurality of locks and the sears thereof, of a single trigger provided with a rearwardly-extending rigidly-attached trigger-blade, a spring-actuated detent-lever pivoted to the trigger-blade, a spring-actuated detent-post pivoted to the frame, a pivoted holding-dog on the trigger-blade adapted to engage the detent-lever and 90 which is adapted for actuation by the sears, a rod which is moved in the act of loading the arm and which acts on said detent-lever, and a movably-supported weight which acts both on the detent-lever and detent-post to throw 95 the same into position for engagement.

7. The combination with a plurality of locks and the sears thereof, of a single trigger provided with a rearwardly-extending rigidly-attached trigger-blade, said trigger-blade being provided with laterally-extending lugs adapted for engagement with the sears, a spring-actuated detent-lever pivoted to the trigger-blade, a tooth on the frame, adapted for engagement with said detent-lever, a holding-dog pivoted on the trigger-blade in position 100 to engage the detent-lever and to be acted upon by the sears when the same are lifted, and a rod which is moved in the act of loading the arm and which acts on said detent-lever.

8. The combination with a plurality of locks and the sears thereof, of a single trigger provided with a rearwardly-extending, rigidly-attached trigger-blade, provided with laterally-extending lugs adapted for contact with 105 the sears, a spring-actuated detent-lever pivoted to the trigger-blade, a tooth on the frame adapted to be engaged by said detent-lever, a holding-dog on the trigger-blade adapted to engage the detent-lever and which is provided 110 with projecting pins, located over the sears in position to be lifted by the same, and a rod which is moved in the act of loading the arm and which acts on said detent-lever.

the gun at the time of firing one of the barrels into striking contact with the said parts, thereby forcing the top of the detent-post M rearwardly and the lower end of the detent-lever N forwardly. This movement of the weight insures interlocking of the detent L with the holding-tooth m and prevents the discharge of the second barrel by the recoil of the arm or by the involuntary pull which occurs after the discharge of the first barrel.

Provision is made for throwing the detent L forwardly or into position for locking engagement with the holding-tooth m by means of actuating connections operated by a part which is moved in the act of loading the arm. As shown in the present instance, said actuating device for the detent is operated from the snap-lever E through the medium of the rod E', which is connected with and actuated by the snap-lever. The sliding bar H extends centrally and rearwardly above the trigger-blade and is of such length that when the snap-lever is actuated and the gun is broken for the purpose of loading the rear end of 5 the said rod H engages the top of the lever N and pushes the same rearwardly, thereby causing a corresponding forward movement of the detent L beneath the holding-tooth m and at the same time permitting the dog O to fall behind the said lever N until the end thereof rests at a point below the pivot n. During this operation the hammers or tumblers are set or cocked and the rear end of 15 the sears are carried downwardly to their lowermost position. One of the said sears is now in contact with the firing-lug, while the sear on the opposite side of the trigger-blade is out of contact with its corresponding firing-lug, the rear or hooked end thereof 20 being on the same elevation as the other sear and directly above the depression. In this position the lateral studs o and o' rest upon the rear ends of the sears, thereby preventing the forward end of the dog O from 25 falling lower than its most effective locking position with respect to the lever N and holding the detent L beneath the holding-tooth m. This is the position the parts assume after the gun has been loaded and is ready for firing and is the position illustrated in Fig. 1, 30 by which it will be seen that the firing-block is adjusted to fire the left barrel first. Upon now pulling the trigger the trigger-blade is lifted, and with it the left sear, sufficiently to 35 discharge the gun. The upward movement of the rear end of the sear raises the dog O out of contact with the lever N. The detent L is so arranged with respect to the holding-tooth m of the detent-post M that when the parts 40 are in position for firing the first barrel, as shown in Fig. 1, the end of said detent will stand beneath the tooth m at such a distance from the same as to permit sufficient upward movement of the trigger-blade to accomplish 45 the firing of the first barrel before the said detent L strikes said tooth. It follows that the upward movement of the trigger-blade and

firing-lugs in the firing of the first barrel is arrested by contact of the said detent L with the tooth m before the second lug on the trigger-blade comes in contact with the second sear. Such contact of the detent-arm with said tooth will prevent further movement of the trigger-blade after the first barrel has been so fired. An involuntary pull invariably follows the 75 first pull, probably by reason of the rebound of the gun from the shoulder and the action of the muscles under the recoil. The purpose of the sliding weight I is to prevent the detent-lever N being thrown back by its spring 80 N' free from the tooth m until after the involuntary pull has taken place, so that the movement of the trigger under the involuntary pull will be blocked by the engagement of said detent L with the tooth m. In the recoil of the arm the weight I will be thrown forward until the arm I' is in position to arrest backward movement of the detent L, so as to retain it in its holding position long enough to insure its contact with the tooth m at the 90 time of the involuntary pull. At the same time that the weight I arrests the backward movement of the detent-lever it also strikes the detent-post M, thereby throwing its upper end rearwardly and further insuring that the 95 detent L and tooth m will stand in interlocked relation to block the involuntary pull when it occurs. This position of the posts is clearly seen in Fig. 8. After the involuntary pull has ceased the weight I is retracted by the spring 100 I', the spring M' pushes the lower end of the lever M rearwardly, which causes a corresponding forward movement of the holding-tooth m, the spring N' throws the lower end of the lever N, with its detent, rearwardly, and the parts of the firing mechanism assume the 105 position shown in Fig. 9, in which, as clearly shown, the rear end of the right sear is in operative contact with the bottom of the depression k² on the right side of the firing-block and the arm is in readiness for the discharge of the second barrel. After the discharge of the second barrel the firing mechanism will be again restored to the position indicated in Fig. 1 by the acts necessary for 115 reloading the arm.

In Fig. 1 I have shown a safety catch or device whereby the firing mechanism may be effectively blocked against all possibility of its discharge during transportation or ordinary handling. The device consists in a depending arm P, integral with the bar p', which slides longitudinally of the arm on the under side of the tang. A longitudinal slot is provided in said tang, and the bar p' is provided with a stud p, which extends upwardly through the said slot and is provided at its top with a thumb-piece or slide P', whereby the said bar, with its depending arm P, may be moved or shifted. When the bar is moved 120 backwardly, so as to bring its depending arm above the stud j³ on the trigger-blade and into engagement with the said stud, any upward movement of the trigger-blade will be 125 130 135

9. The combination with a plurality of locks and the sears thereof, of a single trigger provided with a rearwardly-extending rigidly-attached trigger-blade, a spring-actuated detent-lever pivoted to the trigger-blade, a tooth on the frame adapted for engagement with said detent-lever, a pivoted holding-dog on the trigger-blade adapted to engage the detent-lever and which is adapted for actuation 5 by the sears, a rod which is moved in the act of loading the arm and which acts on said detent-lever, a sliding weight adapted to act on the detent-lever, and a retracting-spring connected with said sliding weight.

10. The combination with a plurality of locks and the sears thereof, of a single trigger provided with a rearwardly-extending trigger-blade, a sliding block mounted on the trigger-blade and provided at each side thereof with elevated and depressed surfaces adapted for contact with the sears, and means for shifting said block from the exterior of the frame 10 comprising a depending stud on said block, a shifting bar provided with a notch which receives the said stud, and a stud on said shifting bar which extends downwardly through a slot in the frame and is provided with an external button adapted to be normally engaged.

15. The combination with a plurality of locks and the sears thereof, of a single trigger provided with a rearwardly-extending trigger-blade, a sliding block mounted on the trigger-blade and provided at each side thereof with elevated and depressed surfaces adapted 20 for contact with the sears, and means for shifting said block from the exterior of the frame.

25. The combination with a plurality of locks and the sears thereof, of a single trigger provided with a rearwardly-extended trigger-blade, a sliding block mounted on the trigger-blade and provided at each side thereof with elevated and depressed surfaces adapted for contact with the sears, and means for shifting said block from the exterior of the frame 30 comprising a depending stud on said block, a shifting bar provided with a notch which receives the said stud, and a stud on said shifting bar which extends downwardly through a slot in the frame and is provided with an external button adapted to be normally engaged.

35. In testimony that I claim the foregoing as my invention I affix my signature, in presence of two witnesses, this 17th day of June, A. D. 40 1899.

In testimony that I claim the foregoing as my invention I affix my signature, in presence of two witnesses, this 17th day of June, A. D. 40 1899.

ALLAN EDWARD LARD.
